(57) **CLAIM**

The ornamental design for a charger as shown and described.

DESCRIPTION

FIG. 1 is a top side isometric view of our new design for a charger.

FIG. 2 is a bottom side isometric view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top side plan view thereof; and,

FIG. 8 is a bottom side plan view thereof.

The uniform broken lines in the drawing figures are for the purpose of illustrating portions of the charger that form no part of the claimed design. The dash dot dash lines in the drawing figures represent boundaries of the claimed design and form no part thereof. The charger is shown with symbolic breaks in its length. The appearance of any portion of the charger between the break lines forms no part of the claimed design.

1 Claim, 5 Drawing Sheets
